UNITED STATES PATENT OFFICE.

PAUL ALGER, OF NEW YORK, N. Y.

DEVICE FOR RENDERING VESSELS UNSINKABLE.

1,280,937.

Specification of Letters Patent.

Patented Oct. 8, 1918.

Application filed May 2, 1918. Serial No. 232,111.

To all whom it may concern:

Be it known that I, PAUL ALGER, a citizen of the United States, and a resident of the city of New York, borough of Manhattan, 5 in the county and State of New York, have invented a new and Improved Device for Rendering Vessels Unsinkable, of which the following is a full, clear, and exact description.

10 This invention relates to a safety appliance for rendering vessels unsinkable against torpedo attack, and the invention has for its general objects to provide simple, novel and effective means in the form of floats applied 15 to the outside of the hull in such a manner that the speed of the vessel is not materially affected when the floats are in normal position close to the side of the hull, as when traveling through waters not infested with 20 submarines, and which can be adjusted to an outstanding position with respect to the hull when in the danger zone, whereby the buoyancy floats will become effective for keeping the vessel afloat if the hull is struck 25 by a torpedo.

A more specific object of the invention is the provision of a plurality of floats arranged on opposite sides of the hull and hingedly connected therewith and having 30 mechanical means for swinging them from a pendent position they assume when not in use, to a horizontal position for use to add extra buoyancy at a point above or where a torpedo usually strikes, the floats being 35 spaced apart so that when they are in outstanding position for use the water can flow between the floats without the latter offering too much resistance.

With such and other objects in view, the 40 invention comprises various novel features of construction and arrangement of parts which will be set forth with particularity in the following description and claims appended hereto.

45 In the accompanying drawings, which illustrate one embodiment of the invention and wherein similar characters of reference indicate corresponding parts in all the views,

Figure 1 is a plan view of a boat showing the floats in outstanding position for use, as in passing through a submarine zone;

Fig. 2 is a fragmentary sectional view showing the safety appliance applied to a boat which is specially constructed to receive it;

Fig. 3 is a similar view showing the

method of adapting the safety device to a boat already in use;

Fig. 4 is a plan view of one of the floats and its operating means; and

Fig. 5 is a detail section on the line 5—5, Fig. 1.

Referring to the drawings, A designates a vessel which has applied to the sides thereof a plurality of floats B which are 65 arranged adjacent or slightly above the floating line, and these floats are adapted to occupy an outstanding position when in use, whereby extra buoyancy is provided to prevent sinking of the vessel if the same 70 should be struck by a torpedo and some of its compartments torn open. These floats when in position of use lie above the depth in which a torpedo travels, so that they will not be struck. The floats normally occupy 75 a position close to the hull when the vessel is traveling through neutral zones or waters not infested with submarines, and being in this position close to the hull the floats do not objectionably decrease the speed of the 80 vessel. The edges a of the floats are beveled to reduce resistance to a minimum, see Fig. 5.

To withstand the upward thrust on the floats when they are in outstanding position, an overhang 1 is provided on the side 85 of the hull by the hull being so built, or this overhang may be in the form of a shelf or flange 1^a fastened to a vessel already in use. The floats are attached to the hull by hinges 2 at such position that when the floats are 90 outstanding they engage the overhang 1 or 1^a to withstand the upward action of the waves. To raise the floats from a pendent position each float has a lifting cable 3, or 95 equivalent means, fastened at 4 to the outer end and passing over a guide pulley 5 and connected with a winding drum 6. For drawing down the float a retracting cable 7 is connected with the outer portion of the float at 8 and passes downwardly to and 100 under a pulley 9, and thence upwardly to the drum 6, whereby the turning of the drum in one direction will wind up one cable, for instance, the cable 3, and pay out the cable 7, whereas turning of the drum in the opposite direction will produce the reverse effect. The drums 6 for the various floats are 105 mounted on shafts 10 at the deck of the vessel, and these shafts may be driven by any suitable means.

The vessel is of such buoyancy that it would float if the floats B were not used, so

that when the floats B are in vertical position they are not relied upon to keep the vessel floating, and when the floats are thrown outwardly into horizontal position for their intended use they will provide necessary buoyancy in case the required buoyancy of the vessel is reduced by being damaged by a torpedo.

From the foregoing description taken in connection with the accompanying drawings, the advantages of the construction and method of operation will be readily understood by those skilled in the art to which the invention appertains, and while I have described the principle of operation, together with the appliance which I now consider to be the best embodiment thereof, I desire to have it understood that the appliance shown is merely illustrative and that such changes may be made when desired as fall within the scope of the appended claims.

Having thus described my invention, I claim as new and desire to secure by Letters Patent:

25 1. The combination of a vessel having a shoulder on the hull at a point adjacent the

water level, floats hinged to the hull at a point below the shoulder and adapted to swing from a vertical position close to the boat to an outstanding horizontal position, 30 with the floats bearing against the shoulder to oppose upward pressure, and means for moving the floats to and from either position.

2. The combination of a boat hull having 35 a shoulder adjacent the water level and horizontal floats connected with the hull and adapted to bear under the shoulder, said floats being all in a common plane and spaced apart with their front and rear edges 40 beveled.

3. The combination of a boat hull, fixed means on the outside of the hull at a point adjacent the water level, and floats hingedly connected with the hull at a point below the 45 said means for permitting the floats to swing from a substantially vertical position to an approximately horizontal position with the floats bearing under the said means and being limited by the latter from upward movement from the horizontal position.

PAUL ALGER.
